UNITED STATES PATENT OFFICE.

HANNAH J. HARE, OF PITTSBURG, PENNSYLVANIA.

DESIGN FOR AN IRONING-BOARD.

SPECIFICATION forming part of Design No. 26,599, dated February 2, 1897.

Application filed September 8, 1896. Serial No. 605,198. Term of patent 7 years.

To all whom it may concern:

Be it known that I, HANNAH J. HARE, a citizen of the United States of America, residing at Pittsburg, in the county of Allegheny and 5 State of Pennsylvania have invented a certain new and useful Design for Ironing-Boards, of which the following is a specification, reference being had therein to the accompanying drawings.

10 This invention relates to a new and original design for an ironing-board, of which the following is a specification, reference being had to the accompanying drawings, showing the same, in which—

15 Figure 1 is a top plan view. Fig. 2 is an underneath plan view.

The principal feature of my design consists of the ironing-board, as herein shown, which

comprises the center piece *c* and side pieces *a* and *b*, said side piece *a* converging outwardly toward the top. The side piece *b* is formed with a shoulder near the upper end, the upper ends of said pieces being gradually curved and the lower ends of same being in a horizontal line. 20 25

Having fully described my invention, what I claim as new is—

The design for an ironing-board, substantially as herein shown and described.

In testimony whereof I affix my signature 30 in presence of two witnesses.

HANNAH J. HARE.

Witnesses:

H. C. EVERET,
H. E. SEIBERT.
